(57) **CLAIM**

The ornamental design for a shingle, as shown and described.

DESCRIPTION

FIG. 1 is a front view of the first embodiment of a strip shingle of the invention;

FIG. 2 is a front view of the second embodiment of a strip shingle of the invention;

FIG. 3 is a front view of the third embodiment of a strip shingle of the invention;

FIG. 4 is a front view of the fourth embodiment of a strip shingle of the invention;

FIG. 5 is a front view of the fifth embodiment of a strip shingle of the invention;

FIG. 6 is a front view of the sixth embodiment of a strip shingle of the invention;

FIG. 7 is a front view of the seventh embodiment of a strip shingle of the invention;

FIG. 8 is a front view of the eighth embodiment of a strip shingle of the invention;

FIG. 9 is a front view of the ninth embodiment of a strip shingle of the invention;

FIG. 10 is a front view of the tenth embodiment of a strip shingle of the invention;

FIG. 11 is a front view of the eleventh embodiment of a strip shingle of the invention;

FIG. 12 is a front view of the twelfth embodiment of a strip shingle of the invention;

FIG. 13 is an end view of the strip shingle of FIGS. 1–12 with the other end view being a mirror image thereof and the top and bottom edges being non ornamental in design;

FIG. 14 is a rear view of the strip shingle of FIGS. 1–3;

FIG. 15 is a rear view of the strip shingle of FIGS. 4–9; and,

FIG. 16 is a rear view of the strip shingle of FIGS. 10–12.

The broken line in the figures showing the portions of the strip shingle is for illustrative purposes only and forms no part of the claimed design.
